(57) **CLAIM**

The ornamental design for a golf putter head, as shown and described.

DESCRIPTION

FIG. 1 is a front perspective view of a golf putter head showing my new design.

FIG. 2 is a top plan view thereof.

FIG. 3 is a bottom plan view.

FIG. 4 is a front elevational view thereof.

FIG. 5 is an toe side elevational view.

FIG. 6 is a rear elevational view thereof.

FIG. 7 is a heel side elevational view; and,

FIG. 8 is a bottom perspective view thereof.

The broken line showing is for illustrative purposes only and forms no part of the claimed design.
